MESNE ASSIGNMENTS, TO AMERICAN BOSCH MAGNETO CORPORATION, OF NEW
YORK, N. Y., A CORPORATION OF NEW YORK.

IMPULSE STARTING MECHANISM.

1,337,331.

Specification of Letters Patent. Patented Apr. 20, 1920.

Application filed September 21, 1917. Serial No. 192,461.

To all whom it may concern:

Be it known that I, WOLFGANG E. SCHWARZMANN, a citizen of the United States, residing at 51 Belleclaire avenue, Long Meadow, Springfield, in the county of Hampden, State of Massachusetts, have invented certain new and useful Improvements in Impulse Starting Mechanism; and I do hereby declare the following to be a full, clear, and 10 exact description of the invention, such as will enable others skilled in the art to which it appertains to make and use the same.

The present invention relates to impulse starting mechanism wherein the driven device is given one or more impulses, each for a fraction of a turn, at a speed considerably higher than the speed of the driving device, and it embodies the use of an impelling spring arranged to be stressed upon relative 20 angular displacement of the driving and driven devices, of locking mechanism for locking the driven device against rotation while the driving device is rotating, and of releasing mechanism for releasing the driven 25 device so that the spring, then stressed, impels the driven device through an appropriate angle. Such mechanism is applicable to various kinds of devices, such as internal combustion engines or other prime movers 30 which are not self-starting; and particularly to magnetos for generating ignition voltages suitable for igniting gaseous mixture present in a cylinder of the engine with which it is associated, when the engine is 35 being turned at low speed in starting, or is at rest in position for an ignition spark.

Many of the devices to which impulse starting mechanism is applicable, may require rotation of the driven device in one 40 direction or the other; for instance, the position or arrangement provided on some engines may require clockwise rotation of the magneto, while others require anticlockwise rotation. In prior forms of construction, 45 the impulse starting mechanism is adapted for rotation of the driven device in a single direction only, and the conditions imposed by the driving devices are met by using intermediate reversing gears, or the like, when 50 made necessary by the fixed direction of rotation of the impulse mechanism, or by providing different right and left hand parts. In accordance with my invention, the use of reversing devices or different right and left

hand parts for the two directions of rotation is avoided by making the impulse mechanism itself reversible, so that it can readily be adapted for rotation of the driven device in one direction or the other merely by changing the relative position of certain 55 parts of the mechanism. In the specific embodiment of the impulse starting mechanism for magnetos hereinafter disclosed as an example of my invention, the impelling spring may be arranged to be stressed upon relative angular displacement in either direction 60 of the magneto shaft and the driving or engine shaft, which may be the engine crank shaft or a shaft geared thereto, the locking member being arranged to lock the magneto 65 shaft against rotation in such angular position for the direction in which it is rotating, and the releasing member being fast on the driving shaft in such angular position relatively to the crank shaft of the engine, for the direction in which it is rotating, 70 that the magneto shaft is always released just prior to the angular position of maximum generation of the magneto and at substantially the beginning of the working 75 stroke of the engine cylinder to be fired. In this way, the magneto is adapted to most effectively generate a spark in the engine cylinder at the time the piston therein is at or near the beginning of its working stroke, 80 irrespective of the direction of rotation of the magneto and without the use of additional gearing or different right and left hand parts. Likewise, the magneto shaft is 85 always released after a predetermined angular displacement of the shafts, that is, after the impelling spring is stressed to the desired degree.

My invention also provides various improvements in construction and arrangement 95 of impulse starting mechanism in general, whether reversible or not. In the preferred embodiment hereinafter disclosed, a disk, mounted on the driving shaft and having integral releasing cams on its periphery, carries circularly-disposed coiled impelling and buffer springs abutting anchorage posts, and a pressure-applying member is loosely journaled on the driving shaft, and has diametrically-disposed arms extending between 100 the impelling and buffer springs. A disk fast on the magneto shaft has a flanged rim 105 with slots and with integral speed limiting

or safety cans, the arms of the pressure-applying member extending through the slots so as to be fast with the magneto shaft. A pawl mounted on a stud journaled in a stationary member is adapted to engage the projecting end of the arm of the pressure-applying member, to thereby lock the magneto shaft against rotation while the driving shaft is rotating, and to stress the impelling spring as a result of the relative angular displacement of the shafts. The pawl may be disengaged from the arm of the pressure-applying member, either by manual operation of an operating handle on the stud, if the driving shaft is stopped, or by the releasing cam, if the driving shaft is allowed to continue its rotation. The impelling force of the spring turns the magneto through an appropriate angle and at a sufficiently high speed to generate a satisfactory ignition spark in the proper engine cylinder, which is primed with gasoline for the purpose, if necessary. If, however, the engine does not start into action, the operation is repeated.

After the engine starts, the speed is sufficient to drive the magneto at sparking speed without the use of the impulse mechanism. In view of this condition, a latch is provided for holding the pawl in inoperative position. Preferably, it consists of a pivoted member pressed by a spring toward the pawl and carrying a finger pressed by a weaker spring to the position for retaining the pawl in inoperative position out of the path of rotation of the projecting ends of the pressure-applying arms.

In this connection, my invention further comprehends the idea of preventing the locking mechanism from fully or partly engaging the driven device while the driving device is rotating at running speed, even if the operator should inadvertently hold the locking mechanism in operative position.

The preferred form of mechanism is made reversible by providing for the two directions of rotation two settings of the pawl and latch, and to corresponding settings of the pressure-applying member and the releasing cams, the position of the springs being changed to correspond therewith.

In the accompanying drawings, illustrating my preferred form of reversible impulse starting mechanism, in application, as an example, to a magneto driven by the engine with which it is associated, Figure 1 shows on a reduced scale the combination of the engine, magneto and impulse mechanism; Fig. 2 is a longitudinal section through the magneto and the impulse mechanism; Figs. 3 and 4 are enlarged sections on line 3-3 and 4-4, respectively, of Fig. 2; Figs. 5 and 6 are perspective views of the locking pawl and the latch therefor; Fig. 7 is a section on line 7-7 of Fig. 8; Fig. 8 is a section on

line 8-8 of Fig. 7, and Figs. 9 and 10 show diagrammatically the relative position of parts of the impulse mechanism for the two directions of rotation.

The engine 1 is of the four-cylinder four-cycle type, and the bipolar magneto 2 driven from the crank shaft 3 thereof by the like gears 4, has its armature 5 extending lengthwise of the arms 6 of the magnet. The mechanical interrupter 7 is located in the arch 8 of the magnet, and is, therefore, in protected position but readily accessible for inspection and repair. The distributor segments 9 are located at the other end of the armature, and at each period of ignition they connect the insulated terminals of the high tension armature winding to two of the spark plugs 10 in series in the well known way. The impulse mechanism is arranged at the outer ends of the arms of the magnet.

The shaft 11, herein termed the driving shaft, is mounted in axial alignment with the shaft 12, herein termed the magneto or driven shaft. The disk 13 is fast with the driving shaft and has on its face two diametrically-disposed anchorage posts 14 bolted thereto and slotted as shown. The pressure-applying member 15 is loosely journaled on the hollow enlarged end 16 of the driving shaft, and has two diametrically-disposed arms 17. The circularly-disposed coiled impelling springs 18 abut the anchorage posts and the arms, and the stiffer and shorter buffer springs 19 abut the other sides thereof. These parts are formed into a unitary structure by the retaining ring 20 loosely threading the springs, the arms and the posts. The retaining ring is initially split at 21 and its two ends are pinned after the parts are in place. The disk has two diametrically-disposed releasing cams 22 normally displaced from the arms 17 by an angle of about 35 degrees.

The disk 23 is fast on the magneto shaft 12 and has a flanged rim 24 with two diametrically-disposed speed limiting or safety cans 25 on its periphery and two pairs of diametrically-disposed slots 26 and 27 located about 27 degrees on the two sides of the cans. As shown best in Figs. 2 and 8, the arms 17 are slipped into one or the other pair of slots to connect the pressure-applying member to the magneto shaft, the arrangement being such that the arms trail the limiting cans and lead the releasing cams in the direction of rotation.

The pawl 28 is loosely journaled on the stud 29, which has an operating handle 30 and a crank arm 31 fast on it. The stud is loosely journaled in a stationary member 125 and tension spring 32 tends to hold the stud and handle in neutral position as shown best in Figs. 3 and 4. The rotation of the pawl on its stud is limited by the shoulders 33 and 34 on the adjacent end faces of the pawl and

crank arm, and the rotation of the crank arm is limited by the stop pin 35. The arrangement is such that with the handle in neutral position, the pawl may rest in operative position on the outer periphery of the rim 24 or it may be in inoperative position in engagement with a latch, as shown in broken lines in Fig. 4. This latch consists of a member 37 loosely journaled on a stud 38 and spring pressed toward the pawl, and carries a loosely journaled finger 39 spring pressed in a direction to retain the pawl. The engaging end of the pawl is squared at 40 to lock the arm of the pressure-applying member, and is beveled at 41 to cooperate with the finger 39. The stop pin 35 is so located that it permits movement of the handle to disengage the pawl from the latch, but it prevents the arms 31 from being turned beyond the position at which the pawl can turn on its stud well above the path of the arms 17 of the pressure-applying member.

The housing for the impulse mechanism consists of a plate 42 having a flange 43 which completes with the magneto the closure for the distributing segments 9. The plate also has an extension 44 forming the base-plate of the magneto, and a bearing 45 for the magneto shaft 12. The other end of the armature is supported in a bearing 46 carried by the base-plate. The cover 47 carries the pawl and the latch, and fits the plate 42 to form a housing chamber for the impulse mechanism. Also, it carries a bearing 48 for the driving shaft.

The operation of the impulse starting mechanism will now be described. For clockwise rotation of the magneto (as viewed from the driving end) the parts are arranged as shown in Figs. 2, 3, 4, 7, 8 and 9. The pawl 28 and the latch 37 are set on the left side of the stud 29 (as viewed from the driving end). The arms 17 of the pressure-applying member are set in the slots 26 of the limiting cam disk 23 and the pawl engages the arm, to lock the magneto shaft 12 against rotation while the driving shaft 11 is rotating, just prior to the angular position of maximum generation of the magneto. The releasing cam disk 13 is so positioned relatively to the angular position of the crank shaft 3 of the engine 1, that the cam releases the pawl at substantially the time the piston in the cylinder to be fired starts its working stroke.

To start the engine into action under its own power, the pawl is first disengaged from the latch by pressing on the operating handle 30, the pawl then turning freely on its stud until it rests on the periphery of the limiting cam disk. The crank shaft of the engine is then turned in any suitable way, the pawl locking the magneto shaft against rotation and causing the pressure-applying member to stress the impelling spring 18 to

the desired degree. If the engine is stopped at or just prior to the position in which the piston starts its working stroke, as is desirable in the case of large engines, the pawl is released by hand by turning the operating handle, but if the rotation of the engine is continued, the pawl is released automatically by the releasing cam, the magneto shaft being impelled in either case at a sufficiently high speed and through an appropriate angle to generate a satisfactory sparking voltage in the magneto. In that period the mechanical interrupter 7 opens and the collector segments 9 connect the secondary winding to two spark plugs 10 in series, whereby an ignition spark occurs in the cylinder to be fired and also in a cylinder in which the piston is at or near the end of its exhaust stroke. In almost all cases in which the cylinder contains gas, or is properly primed with gasoline, the engine starts upon the first operation of the impulse mechanism; but if, for any reason, this does not occur, the crank shaft is again turned or its rotation is continued until the piston of the next cylinder to be fired is at or near the beginning of its working stroke, and the impulse mechanism is again operated.

Ordinarily the pawl is thrown into latching position when it is released by the releasing cam, but if it remains in operative locking position, or if for any reason it comes into that position, it is thrown into latched position by the limiting cams and prevented thereby from partly or fully engaging the projecting ends of the arms of the pressure-applying member as soon as the speed exceeds a value at which the mechanism might be damaged by the resulting check. Even if the operator should then hold the handle in its extreme position limited by engagement of the arm 31 and pin 35, the free rotatable movement of the pawl on its stud suffices to permit the limiting cams to throw the pawl out of the path of the arms of the pressure-applying member as they pass.

If the impulse mechanism is to be arranged for driving a magneto in anticlockwise direction, instead of in clockwise direction as hereinbefore described, it is only necessary to change the position of certain of the parts of the mechanism as indicated in Figs. 9 and 10. The pawl 28 is set on the other side of its stud 29, the shoulders 33 and 34 being arranged for that purpose to permit the same limited amount of rotation of the pawl on the stud as before. The member 37 of the latch is reversed on its stud 38 and is mounted at 49 on the cover 47 of the housing to cooperate with the pawl as before, and the pin is set on the other side of the stud. The impelling and buffer springs are set to abut the opposite sides of the anchorage posts 14, and the pressure-

applying member is arranged in the position in which its arms 17 extend between the impelling and buffer springs. The releasing cam disk 13 is so positioned in angular position relatively to the crank shaft of the engine, that the releasing cams 22 cooperate with the pawl at substantially the same angular position of the crank shaft of the engine as before. The releasing cam disk 10 is adjusted in this way by means of the gears 4, or if the releasing cam disk is mounted directly on the crank shaft of the engine, the adjustment is effected by adjusting it on the crank shaft. Having the releasing cam disk and the pressure-applying member in their new positions, the arms 17 are then inserted into the slots 27 on the sides of the limiting cams opposite to that for the other direction of rotation, so that 20 for both directions the arms trail the limiting cams 25 and lead the releasing cams 22, in the direction in which they are rotating. In this way the magneto shaft 12 is locked against rotation just prior to the angular 25 position of maximum generation of the magneto, and is unlocked, after a predetermined angular displacement of the shafts sufficient to stress the impelling spring to the desired degree, and also at the time that the crank 30 shaft 3 reaches the position in which the piston in the cylinder to be fired is, as before, at or near the beginning of its working stroke.

It will be apparent that the magneto may 35 be of any suitable type, and that the engine may have any number of cylinders operating on any desired cycle.

Having thus described my invention, what I claim is:

40 1. The combination with an internal combustion engine having a shaft and a magneto therefor having a shaft, of reversible impulse starting mechanism for the magneto comprising an impelling spring arranged to be stressed upon relative angular displacement of the shafts, a locking member for locking the magneto shaft against 45 rotation while the engine shaft is rotating, and a releasing member carried by the engine shaft and being constructed and arranged so that for each direction of rotation the locking member is released at the 50 same angular displacement of the shafts.

55 2. In reversible impulse starting mechanism, a driving shaft, a driven shaft, an impelling spring arranged to be stressed upon relative angular displacement of the shafts, a locking member having one position for locking the driven shaft while the driving shaft is rotating in one direction and another position for locking the driven shaft while the driving shaft is rotating in the other direction, and a releasing member for releasing the locking member, the releasing member being mounted on the driving shaft and having two angular positions relatively to the driven shaft such that for either direction of rotation the releasing member releases the locking member at the same angular displacement of the shafts.

60 3. In reversible impulse starting mechanism, a driving shaft, a driven shaft, a spring 65 displacement of the shafts, a locking mem-

ber having one position for locking the magneto shaft just prior to the position of maximum generation of the magneto while the engine shaft is rotating in one direction and another position for locking the magneto shaft just prior to the position of maximum generation of the magneto while the engine shaft is rotating in the other direction, and a releasing member constructed and arranged so that for each direction of rotation the magneto shaft is released at substantially the same angular position of the engine shaft.

3. The combination with an internal combustion engine having a shaft and a magneto therefor having a shaft, of reversible impulse starting mechanism for the magneto comprising an impulse spring arranged to be stressed upon relative angular displacement of the shafts, a locking member constructed and arranged so that for each direction of rotation the magneto shaft is locked just prior to the position of maximum generation of the magneto, and a releasing member carried by the engine shaft for releasing the locking member, the releasing member being carried at a different angular position for each direction of rotation so that the magneto shaft is released at substantially the same angular position of the engine shaft irrespective of the direction of rotation.

4. The combination with an internal combustion engine having a shaft and a magneto therefor having a shaft, of reversible impulse starting mechanism for the magneto comprising an impelling spring arranged to be stressed upon relative angular displacement of the shafts, a locking member for locking the magneto shaft against rotation while the engine shaft is rotating, and a releasing member carried by the engine shaft and being constructed and arranged so that for each direction of rotation the locking member is released at the same angular displacement of the shafts.

5. In reversible impulse starting mechanism, a driving shaft, a driven shaft, an impelling spring arranged to be stressed upon relative angular displacement of the shafts, a locking member having one position for locking the driven shaft while the driving shaft is rotating in one direction and another position for locking the driven shaft while the driving shaft is rotating in the other direction, and a releasing member for releasing the locking member, the releasing member being mounted on the driving shaft and having two angular positions relatively to the driven shaft such that for either direction of rotation the releasing member releases the locking member at the same angular displacement of the shafts.

6. In reversible impulse starting mechanism, a driving shaft, a driven shaft, a spring

- arranged to be stressed upon relative angular displacement of the shafts, a pivoted pawl having one position for locking the driven shaft while the driving shaft is rotating in one direction and another position for locking the driver shaft while the driving shaft is rotating in the other direction, said pawl being arranged on one side of its pivot for rotation in one direction and on the other side of its pivot for rotation in the opposite direction, and a pawl-releasing cam mounted on the driving shaft to release the pawl at one angular position of the driven shaft for rotation in one direction and at another angular position for rotation in the opposite direction.
7. In reversible impulse starting mechanism, a driving shaft, a driven shaft, a spring connected to one of the shafts, a pressure-applying member adapted to stress the spring upon relative angular displacement of the shafts, a locking member having one position for locking said member and the driven shaft while the driving shaft is rotating in one direction and another position for locking said member and the driven shaft while the driving shaft is rotating in the other direction, and a releasing member for releasing the locking member, the releasing member being mounted on the driving shaft in either of two angular positions relatively to the driven shaft such that for either direction of rotation the releasing member releases the locking member at the same angular displacement of the shafts.
8. In reversible impulse starting mechanism, a driving shaft, a driven shaft, a spring connected to the driving shaft, a pressure-applying member for the spring connected in one angular position relatively to the driven shaft for rotation in one direction and in another angular position for rotation in the opposite direction, a locking member having one position for locking the pressure-applying member and the driven shaft while the driving shaft is rotating in one direction and another position for locking the pressure-applying member and the driven shaft while the driving shaft is rotating in the other direction, said members co-operating at one angular position of the driven shaft for rotation in one direction and at another angular position for rotation in the opposite direction, and a releasing member for releasing the locking member at one angular position of the driven shaft for rotation in one direction and at another angular position for rotation in the opposite direction.
9. In reversible impulse starting mechanism, a driving shaft, a driven shaft, a spring connected to the driving shaft, a pressure-applying member adapted to stress the spring upon relative angular displacement of the shafts, said member being fastened to the driven shaft in one position for rotation in one direction and in another position for rotation in the opposite direction, a pawl having one position for locking the member while the driving shaft is rotating in one direction and another position for locking the member while the driving shaft is rotating in the other direction, said pawl having one position of co-operation with said member for rotation in one direction and another position of co-operation for rotation in the opposite direction, and a pawl-releasing cam carried by the driving shaft in one angular position relatively to the driven shaft for rotation in one direction and in another angular position for rotation in the opposite direction.
10. In reversible impulse starting mechanism, a driving shaft, a driven shaft, a spring arranged to be stressed upon relative angular displacement of the shafts, a pivoted pawl having one position for locking the driven shaft while the driving shaft is rotating in one direction and another position for locking the driven shaft while the driving shaft is rotating in the other direction, the pawl being arranged on one side of its pivot for rotation in one direction and on the other side of the pivot for rotation in the opposite direction, a latch for holding the pawl in inoperative position, a mounting for supporting the latch for one position of the pawl, another mounting for supporting the latch for the other position of the pawl, and a releasing member actuated by the driving shaft for releasing the pawl from locking position with the driven shaft.
11. In reversible impulse starting mechanism, a driving shaft, a driven shaft, a spring connected to the driving shaft, a disk fast with the driven shaft and having a flange with two adjacent slots, a pressure-applying arm adapted to stress the spring upon relative angular displacement of the shaft, said arm projecting through one of said slots for rotation in one direction and through the other of said slots for rotation in the opposite direction, a pawl engageable with the projecting end of said arm to lock the driven shaft against rotation, and a pawl-releasing cam mounted on the driving shaft, the pawl and its releasing cam being arranged to co-operate for releasing said arm at one angular position of the driven shaft for rotation in one direction and at another angular position for rotation in the opposite direction.
12. In reversible impulse starting mechanism, a driving shaft, a driven shaft, a spring connected to the driving shaft, a limiting cam fast with the driven shaft, a pressure-applying member adapted to stress the spring upon relative angular displacement of the shafts, said member being connected in one position to the limiting cam

- 6
- for rotation in one direction and in another position for rotation in the opposite direction, a pawl engageable with said member to lock the driven shaft against rotation, and 5 a pawl-releasing cam fast with the driving shaft, the pawl and its releasing cam being arranged to coöperate at two angular positions of the driven shaft for the two directions of rotation.
- 10 13. In reversible impulse starting mechanism, a driving shaft, a driven shaft, a spring connected to the driving shaft, a limiting cam fast with the driven shaft, a pressure-applying member adapted to stress the spring upon relative angular displacement of the shafts, a locking member adapted to lock the pressure-applying member against rotation while the driving member is rotating, and a releasing member for 15 releasing the locking member, said pressure-applying and releasing members being arranged for connection to the driven and driving shafts, respectively, in two positions so that for each direction of rotation the 20 pressure-applying member trails the limiting cam and leads the releasing member.
14. In reversible impulse starting mechanism, a driving shaft, a driven shaft, a spring connected to the driving shaft, a 25 limiting cam, a pressure-applying member adapted to stress the spring upon relative angular displacement of the shafts, a locking member adapted to lock the pressure-applying member against rotation while the 30 driving member is rotating, and a releasing member for releasing the locking member, the limiting cam and the pressure-applying member being arranged for connection to the driven shaft in two positions and the releasing member being arranged for connection to the driving shaft in two positions so that for each direction of rotation the 35 pressure-applying member trails the limiting cam and leads the releasing member.
- 40 15. In impulse starting mechanism, a driving shaft, a driven shaft, a member fast with the driven shaft, a coiled impelling spring, a pressure-applying member loosely journaled on the driving shaft and having radially projecting arms engaging the spring, a retaining member threading the spring and the arm, locking mechanism constructed and arranged to lock the driven shaft against rotation while the driving shaft is 45 rotating and thereby stress the spring, and releasing mechanism for the locking mechanism.
- 50 16. In impulse starting mechanism, a driving shaft, a driven shaft, a disk mounted on the driving shaft and having an anchorage post on its face, a circularly-disposed coiled impelling spring abutting the post, a pressure-applying member loosely journaled on the driving shaft and having 55 radially projecting arms engaging the
- spring, a retaining ring threading the spring and the post, locking mechanism constructed and arranged to lock the driven shaft against rotation while the driving shaft is rotating and thereby stress the spring, and 60 releasing mechanism for the locking mechanism.
17. In impulse starting mechanism, a driving shaft, a driven shaft, a member fast on the driving shaft, and having anchorage posts, circularly-disposed coiled impelling springs abutting the posts, a pressure-applying member loosely journaled on the driving shaft and having radially-projecting arms engaging the springs, a retaining ring threading the springs and arms, locking mechanism constructed and arranged to lock the driven shaft against rotation while the driving shaft is rotating and thereby stress the impelling spring, and 65 releasing mechanism for the locking mechanism.
18. In impulse starting mechanism, a driving shaft, a driven shaft, a disk mounted on the driving shaft and having diamet- 70 rically-disposed anchorage posts, circularly-disposed coiled impelling springs abutting the posts, a pressure-applying member loosely journaled on the driving shaft and having diametrically-disposed arms engag- 75 ing the springs, a retaining ring threading the springs and arms and engaging the posts, locking mechanism constructed and arranged to lock the driven shaft against rotation while the driving shaft is rotating and thereby stress the spring, and releasing mechanism for the locking mechanism.
- 80 19. In impulse starting mechanism, a driving shaft, a driven shaft, a disk mounted on the driving shaft and having diamet- 85 rically-disposed anchorage posts, circularly-disposed coiled impelling springs abutting the posts, a pressure-applying member loosely journaled on the driving shaft and having diametrically-disposed arms engag- 90 ing the springs, a retaining ring threading the springs and arms and engaging the posts, locking mechanism constructed and arranged to lock the driven shaft against rotation while the driving shaft is rotating and thereby stress the spring, and releasing mechanism for the locking mechanism.
- 95 20. In impulse starting mechanism, a driving shaft, a driven shaft, a disk mounted on the driving shaft and having diamet- 100 rically-disposed anchorage posts, circularly-disposed coiled impelling springs abutting the posts, a pressure-applying member loosely journaled on the driving shaft and having diametrically-disposed arms engag- 105 ing the springs, a retaining ring threading the springs and arms and engaging the posts, locking mechanism constructed and arranged to lock the driven shaft against rotation while the driving shaft is rotating and thereby stress the spring, and releasing mechanism for the locking mechanism.
- 110 21. In impulse starting mechanism, a shaft, a disk fast on said shaft and having anchorage posts on its face and a cam portion on its periphery, circularly-disposed coiled impelling and buffer springs abutting the posts, a pressure-applying member loosely journaled on said shaft and having arms 115 projecting between the impelling and buffer springs, and a retaining ring threading said springs, posts and arms; a driven shaft; and locking mechanism for locking the pressure-applying member and the driven shaft against rotation while the driving shaft is rotating; said cam portion being engageable with said mechanism to release it from locking position.
- 120 22. In impulse starting mechanism, a driving shaft, a driven shaft, an impelling spring connected to the driving shaft, a disk fast on the driven shaft and having a flange with a slot and a cammed portion, a pressure-applying member loosely journaled on the driving shaft and extending through said slot, said member being adapted to stress the spring upon relative angular displacement of the shafts, a locking member for locking the driven shaft 125
- 130

against rotation while the driving shaft is rotating, and a releasing member for releasing the locking member.

21. In impulse starting mechanism, a driving shaft, a driven shaft, an impelling spring connected to the driving shaft, a disk fast on the driven shaft and having a flange with a speed limiting cam and a slot on either side thereof, a pressure-applying member extending into the slot trailing the cam in the direction of rotation and adapted to stress the spring upon relative angular displacement of the shafts, a locking member for locking the driven shaft against rotation while the driving shaft is rotating, and a releasing member for releasing the locking member.

22. In impulse starting mechanism, a driving shaft, a driven shaft, an impelling spring connected to the driving shaft, a disk fast on the driven shaft and having a flange with diametrically-disposed limiting cams and a slot on either side of each cam, a pressure-applying member having diametrically-disposed arms extending into the pair of slots that trails the respective cams, said member being adapted to stress the spring upon relative angular displacement of the shafts, a locking member for locking the driven shaft against rotation while the driving shaft is rotating, and a releasing member for releasing the locking member.

23. In impulse starting mechanism, a driving shaft, a driven shaft, an impelling spring arranged to be stressed upon relative angular displacement of the shafts, an oscillatory stud, a pawl adapted to lock the driven shaft against rotation while the driving shaft is rotating and having a limited angle of rotation on the stud, and means for releasing the pawl from locking engagement with the driven shaft.

24. In impulse starting mechanism, a driving shaft, a driven shaft, an impelling spring arranged to be stressed upon relative angular displacement of the shafts, a pawl adapted to lock the driven shaft against rotation while the driving shaft is rotating, a stud on which the pawl is pivoted, a coupling providing a limited angle of rotation of the pawl on the stud, and means for releasing the pawl from locking engagement with the driven shaft.

25. In impulse starting mechanism, a driving shaft, a driven shaft, an impelling spring arranged to be stressed upon relative angular displacement of the shafts, a pawl adapted to lock the driven shaft against rotation while the driving shaft is rotating, an operating handle having a limited angle of rotation relatively to the pawl, and means for releasing the pawl from locking engagement with the driven shaft.

26. In impulse starting mechanism, a driving shaft, a driven shaft, an impelling

spring arranged to be stressed upon relative angular displacement of the shafts, a stud, an operating handle for the stud, a pawl mounted on the stud and adapted to lock the driven shaft against rotation while the driving shaft is rotating, a loose coupling between the handle and pawl providing relative angular displacement between them, and means for releasing the pawl from locking engagement with the driven shaft.

27. In impulse starting mechanism, a driving shaft, a driven shaft, an impelling spring arranged to be stressed upon relative angular displacement of the shafts, a stud, an operating handle fast on the stud, a pawl loosely journaled on the stud for a limited angle of rotation thereon, said pawl being adapted to lock the driven shaft against rotation while the driving shaft is rotating, and means for releasing the pawl from locking engagement with the driven shaft.

28. In impulse starting mechanism, a driving shaft, a driven shaft, an impelling spring arranged to be stressed upon relative angular displacement of the shafts, a stud journaled in a stationary member, a pawl journaled on the stud for a limited angle of rotation thereon, said pawl being adapted to lock the driven shaft against rotation while the driving shaft is rotating, an operating handle fast on the stud, a spring connected to the stud and tending to hold the operating handle in a neutral position, and means for releasing the pawl from locking engagement with the driven shaft.

29. In impulse starting mechanism, a driving shaft, a driven shaft, an impelling spring arranged to be stressed upon relative angular displacement of the shafts, an oscillatory stud, a latch, a pawl having an operative position in locking engagement with the driven shaft to lock it against rotation while the driving shaft is rotating, and an inoperative position in engagement with the latch, said pawl being journaled on said stud for limited rotative movement thereon from one to the other of said positions, and means for releasing the pawl from locking engagement with the driven shaft.

30. In impulse starting mechanism, a driving shaft, a driven shaft, an impelling spring arranged to be stressed upon relative angular displacement of the shafts, a stud, a latch, a pawl having an operative position in locking engagement with the driven shaft to lock it against rotation while the driving shaft is rotating, and an inoperative position in engagement with the latch, a loose coupling between the stud and pawl permitting the pawl to turn relatively to the stud from one to the other of said positions, an operating handle for turning the stud to take up the play in the coupling and then positively move the pawl from one to the other of said positions, and means

for releasing the pawl from locking engagement with the driven shaft.

31. In impulse starting mechanism, a driving shaft, a driven shaft, an impelling spring arranged to be stressed upon relative angular displacement of the shafts, an oscillatory stud, a pawl adapted to lock the driven shaft against rotation while the driving shaft is rotating and having a limited angle of rotation on the stud, a spring tending to hold the stud in fixed angular position, and means for releasing the pawl from locking engagement with the driven shaft.

32. In impulse starting mechanism, a driving shaft, a driven shaft, an impelling spring arranged to be stressed upon relative angular displacement of the shafts, a stud, a latch, a pawl having an operative position in locking engagement with the driven shaft to lock it against rotation while the driving shaft is rotating, and an inoperative position in engagement with the latch, a loose coupling between the stud and pawl permitting the pawl to turn relatively to the stud from one to the other of said positions, an operating handle for turning the stud to take up the play in the coupling and then positively move the pawl from one to the other of said positions, a spring tending to hold the coupling in position for the pawl to turn relatively to the stud from one to the other of said positions, and means for releasing the pawl from locking engagement with the driven shaft.

33. In impulse starting mechanism, a driving shaft, a driven shaft, an impelling spring arranged to be stressed upon relative angular displacement of the shafts, an oscillatory stud, a latch, a pawl having an operative position in locking engagement with the driven shaft to lock it against rotation while the driving shaft is rotating, and an inoperative position in engagement with the latch, said pawl being journaled on said stud for limited rotative movement thereon from one to the other of said positions, a safety cam co-operative with the pawl, and means for releasing the pawl from locking engagement with the driven shaft.

34. In impulse starting mechanism, a driving shaft, a driven shaft, a spring ar-

ranged to be stressed upon relative angular displacement of the shafts, an oscillatory stud, a pawl journaled on the stud for a limited angle of rotation thereon, said pawl being adapted to lock the driven shaft against rotation while the driving shaft is rotating, means for releasing the pawl from locking engagement with the driven shaft, and means limiting the angular movement of the stud.

35. In impulse starting mechanism, a driving shaft, a driven shaft, an impelling spring arranged to be stressed upon relative angular displacement of the shafts, an oscillatory stud, a pawl having an operative position in locking engagement with the driven member and being journaled on the stud for angular movement thereon, a stop pin limiting the angular movement of the pawl to a position in which it may turn on the stud from operative to inoperative position, a safety cam co-operative with the pawl, and means for releasing the pawl from operative engagement with the driven shaft.

36. In impulse starting mechanism, a driving shaft, a driven shaft, a spring arranged to be stressed upon relative angular displacement of said shaft, a pawl adapted to lock the driven shaft against rotation when the driving shaft is rotating, and a latch for holding the pawl in inoperative position, said latch comprising a spring-pressed pivoted member carrying a spring-pressed pivoted finger engageable with the pawl so that the pawl can raise the finger to become locked behind it in inoperative position whereas the member is movable against the spring to release the pawl from the finger.

37. In impulse starting mechanism, a driving shaft, a driven shaft, a spring arranged to be stressed upon relative angular displacement of the shafts, a pawl for locking the driven shaft against rotation while the driving shaft is rotating, and a pivoted latch for holding the pawl in inoperative position, said latch being pressed toward the pawl by a spring and having a pivoted finger which is pressed by a weaker spring to the position for retaining the pawl in inoperative position.

In testimony whereof I affix my signature.
WOLFGANG E. SCHWARZMANN.
